COMBINED CASTER CHAIR AND TRAY FOR INVALID

Thomas E. Bowen, Birmingham, Ala., assignor to South-
eastern Metals Division of U.S. Industries, Inc.

Filed Apr. 17, 1970, Ser. No. 22,487

Term of patent 7 years

Int. Cl. D6—02

U.S. Cl. D15—1

FIG. 1.

FIG. 2.

FIG. 2.

FIG. 3.

FIG. 1 is a front perspective view of a combined caster chair and tray for invalid showing my design.

FIG. 2 is an enlarged side view thereof taken on the side opposite to FIG. 1.

FIG. 3 is an enlarged front view of the design; and FIG. 4 is a back view thereof.

I claim:

The ornamental design for a combined caster chair and tray for invalid, as shown.
